UNITED STATES PATENT OFFICE.

ALEXANDER THOMSON AND MALACHA JOSEPH McLAUGHLIN, OF SOURLAKE, TEXAS.

HYDRAULIC SWIVEL.

No. 800,185.

Specification of Letters Patent.

Patented Sept. 26, 1905.

Application filed April 25, 1905. Serial No. 257,393.

To all whom it may concern:

Be it known that we, ALEXANDER THOMSON and MALACHA JOSEPH McLAUGHLIN, citizens of the United States, residing at Sourlake, in the county of Hardin and State of Texas, have invented certain new and useful Improvements in Hydraulic Swivels; and we do hereby declare the following to be a full, clear, and exact description of the invention, such as will enable others skilled in the art to which it appertains to make and use the same.

Our invention relates to that class of hydraulic swivels designed for use in connection with rotary well-drilling machines where water is conducted under heavy pressure from a pump to the point of a drill secured to the lower end of a rotating tube.

The invention contemplates an organization of cooperating elements whereby a supply-hose may be supported in a given position and retained against movement in relation to the rotating drill-tube while supplying it with water.

The device consists, primarily, of a swivel-block and supporting means therefor, a tubular swivel-stem extending through said block, and means provided for rotatably supporting same.

Other objects and advantages of this invention will appear in the following description, and the novel features thereof will be particularly pointed out in the appended claims, it being understood that changes in the form, proportion, and minor details of construction may be resorted to without departing from the spirit or sacrificing any of the advantages of the invention.

In the drawing the figure represents a longitudinal vertical central section illustrating the construction of a hydraulic swivel embodying the features of our invention.

In making wells by the rotary process it is necessary to continually force water to the drill-point attached to the lower end of the well-casing and rotate said casing while being supplied with water. Several devices have been invented for accomplishing this; but all use a hose-stem and swivel-stem, also other complications for the purpose. As disclosed in the accompanying drawing, our swivel with but one stem supports the water-supply pipe in a stationary condition while the casing is rotated, thus much more simply attaining the desired object.

Referring more particularly to the drawing, A denotes a bail or clevis of any preferred form enlarged and apertured at its ends, as at B B, and having bearings on the projecting reduced ends of the hollow trunnion-block C, which block revolvably surrounds the swivel-stem D. The trunnion-block C, as suggested, is hollow and is formed with an interior annular chamber for purposes which will be hereinafter made apparent. The swivel-stem D is exteriorly threaded at the lower end and a casing-bushing E fitted to same. A jam-collar F is also threaded upon it for firmly locking the two and obviating danger of said bushing working loose and unscrewing with the casing-section to be connected to the lower end of said bushing. A collar G surrounds stem D just below and preferably formed integral with the trunnion-block C. It is chambered, forming a stuffing-box H, which is filled with suitable packing material. A gland I is threaded into the lower end of said collar G for adjustably closing said stuffing-box H and retaining the packing in position.

Mounted within and resting upon the inner lower surface of the trunnion-block C is an annular collar J, and a similar collar K is placed above collar J, the space between said collars being maintained by means of conical rollers L or other antifriction devices traveling within annular raceways M and N, formed in the said collars for limiting the lateral play of said cones.

Forming part of the swivel-stem is a solid collar O, the lower side resting upon collar K. A head P, secured by stud-bolts Q, closes the annular chamber of trunnion-block C and rests upon collar O, whereby a tight closure is made for it, also for collars J and K, retaining all against vertical movement, besides forming a receptacle that may be filled with oil and kept free of dirt.

R is an extension of the head P. It is exteriorly threaded and chambered, forming an annular stuffing-box S, having a gland T adjustably secured in position by a superimposed annular cap U, interiorly threaded and provided with an inner annular shoulder resting upon the flange of gland T, whereby the packing is adjustably compressed around the swivel-stem D. A jam-collar V, screwed on upper end of gland T, prevents the weight of hose resting upon the packing. A gooseneck W is threaded into the upper end of the gland

T and carries a suitable union or coupling X, adapted to receive any preferred form of supply-hose Y.

- 5 The operation of our improved device is as follows: The bail A, being supported by any preferred tackle carried by a suitable derrick, supports the elements carried by the trunnion-block, and the parts are brought into line with the section of the well-boring tube, 10
- 10 The casing-bushing on the lower end of swivel-stem D is connected to a joint of casing, and the said section of casing, together with the improved swivel, is raised to a vertical position and connected with the casing already in 15 the well. The water may now be forced through the hose connection X, whence it will find its way down through the swivel-stem D and into the casing, down which it passes, finding exit through holes for the purpose 20 formed in the drill-point that is screwed to the bottom end of the string of casing, the said casing being given a rotary motion by any of the well-known means, said casing and rotating means not being shown. During operation the swivel-stem D, collar K, the jam-collar F, and casing-bushing E will revolve 25 with the casing, to which the parts are connected. The collar J, bail A, trunnion-block C, with all its other connections, including 30 supply-hose connections, will remain stationary. It will be apparent that leakage of water from the swivel-stem will be prevented by means of the packing within the stuffing-boxes S and H.
- 35 Having thus described our invention, we claim as new and desire to secure by Letters Patent—

1. In a hydraulic swivel, the combination with a trunnion-block and a bail supporting 40 the same, of a swivel-stem extending through

said block, a collar surrounding said swivel-stem, a similar collar spaced above the first-mentioned collar, antifriction means interposed between said collars all within said trunnion-block and a head secured to said trunnion-block and entirely inclosing said collars and antifriction means. 45

2. In a hydraulic swivel, the combination with a suitable support, of a swivel-stem, a collar surrounding the same, a collar carried by 50 said stem, antifriction-bearings interposed between said collars, a solid collar on said swivel-stem forming a bearing for the uppermost collar, all inclosed within a trunnion-block.

3. A hydraulic swivel, comprising a trunnion-block, a bail for lifting the same swiveled thereto, a swivel-stem passing through 55 said trunnion-block, and acting also as a hose-stem, an annular collar surrounding said swivel-stem, a similar collar above the same, 60 both within said trunnion-block, a stuffing-box surrounding the upper end of said swivel-stem, antifriction means interposed between said collars, and means for retaining said collars and antifriction means in position, substantially as herein specified. 65

4. A hydraulic swivel, comprising a swivel-stem, open at both ends, means for revolvably supporting same, a stuffing-box surrounding the upper end thereof, means for closing said 70 stuffing-box, and a similar stuffing-box below trunnion-block for retaining oil within said trunnion-block, substantially as described.

In testimony whereof we affix our signatures in presence of two witnesses.

ALEXANDER THOMSON,
MALACHA JOSEPH McLAUGHLIN.
